UNITED STATES PATENT OFFICE.

AARON HARRIS AND CHARLES STAHL, OF NEW YORK, N. Y.

DRUGGIST'S AND MEDICINE LABEL.

SPECIFICATION forming part of Letters Patent No. 606,457, dated June 28, 1898.

Application filed December 17, 1895. Serial No. 572,488. (No model.)

To all whom it may concern:

Be it known that we, AARON HARRIS and CHARLES STAHL, citizens of the United States, residing at New York, in the county of New York and State of New York, have invented certain new and useful Improvements in Druggists' and Medicine Labels; and we do hereby declare the following to be a full, clear, and exact description of the invention, such as will enable others skilled in the art to which it appertains to make and use the same.

The object of our invention is to indicate with ease and facility the time when the next or proximate dose of medicine is to be taken or exhibited. We effect this object in the following manner:

Upon the label L, which is generally of the ordinary gummed-paper variety, we cause to be printed in any convenient manner the impress of a clock-dial C, as shown in the accompanying drawings, Figure 1. Suitably attached to this dial is a hand or pointer P, that can be moved around the dial, being set into the label by an eyelet E, and pivoted on said eyelet, as shown in Fig. 2 of the accompanying drawings, at p.

It is obvious now that our invention is described that it may be carried into effect in numerous ways. For instance, on any usual label the impress of the clock face or dial may be made with a rubber stamp, and the pointer set in such face and pivoted on an eyelet set

in the label with an ordinary eyelet punch and set, or the impress may be printed on when the label is printed.

We are aware that detached devices having a pointer moving over a dial have been previously employed; but these devices are subject to the defect in use of being easily mislaid or if two or more medicines are being alternately or otherwise exhibited of being misapplied to the glasses or receptacles. Our device being fixedly attached to the bottle cannot be misplaced or misapplied and is therefore an integral device.

Having described our invention, what we claim, and desire to secure by Letters Patent of the United States, is—

As an improved article of manufacture, a combined druggist's time-indicating and direction label, comprising a flexible card, a clock-dial imprinted thereon, a rotary indicating-hand therefor; the remaining portion of said card being appropriately lettered and ruled for said direction, substantially as described.

In testimony whereof we have affixed our signatures in presence of two witnesses.

AARON HARRIS.
CHARLES STAHL.
